UNITED STATES PATENT OFFICE

CHARLES EARNEST AUSTIN, OF SALMON FALLS, NEW HAMPSHIRE, ASSIGNOR
TO HIMSELF AND SAMUEL GILMAN PHILPOT, OF SAME PLACE.

REIN-HOLDER.

SPECIFICATION forming part of Letters Patent No. 360,264, dated March 29, 1867.

Application filed November 30, 1866. Serial No. 220,304. (No model.)

To all whom it may concern:

Be it known that I, CHARLES EARNEST AUSTIN, of Salmon Falls, in the county of Strafford and State of New Hampshire, have invented 5 a new and Improved Rein-Holder, of which the following is a full, clear, and exact description.

My invention relates to a holder for supporting driving-reins at points between an animal's bit and the terrets or rein-loops on the saddle of a harness; and the invention has for its object to provide a simple, inexpensive, efficient, and durable device of this character.

The invention consists in certain novel features of construction and combinations of parts 15 of the rein-holder, all as hereinafter fully described and claimed.

Reference is to be had to the accompanying drawings, forming a part of this specification, 20 in which similar letters of reference indicate corresponding parts in all the figures.

Figure 1 is a side view of a harnessed horse, and illustrates the manner of using the improved rein-holder. Fig. 2 is a front view of 25 the rein-holder, drawn about full size. Fig. 3 is a longitudinal sectional view of the holder, taken on the line *x x*, Fig. 2. Fig. 4 is a rear face view of the rein-holder; and Fig. 5 is a transverse section of the holder, taken on the 30 line *y y*, Fig. 3.

The rein-holder consists of a plate of elastic metal cut or stamped out to form a body or base-plate, A, opposite end tongues, B C, and attaching lips or tags D D. The tongue B is 35 shorter than the tongue C, so that when the former is bent over and in front of the base-plate A its end will stand about in line with the center of the base-plate, and when the tongue C is bent over from the other end of 40 the base-plate it will lap upon the tongue B and extend nearly to the end bend, b, thereof, and the extremity c of the tongue C is bent outward a little from the face of the tongue B, to allow the rein to be passed between the tongues 45 B C and into the space E, between the tongues and base-plate of the holder, and this space E is intended to be of proper size to cause the rein slipped into the holder to be firmly held or clamped flatwise between the elastic tongues 50 and the base-plate A of the holder.

The lips or tags D D, which are simply stamped back from the base-plate A of the holder, are passed through holes made for them in the neck or shoulder strap F, which supports the breast-collar G of the harness, and 55 the protruding ends of the tags are then clinched or hammered down at the inner face of the neck-strap, to attach the rein-holder thereto in the position indicated in Fig. 1 of the drawings, one of the rein-holders being 60 fixed to each side of the neck-strap, thereby allowing the reins H, passing from each end of the bit I to the saddle terrets or hooks J at opposite sides of the horse, to be snapped into the rein-holders, and which may be very 65 quickly and easily done.

As most clearly shown in Fig. 5 of the drawings, the base-plate A of the rein-holder is pressed into concavo-convex form transversely, and its concaved face will lie against the 70 neck-strap F, to which it is secured, and the tongues B C of the holder are also pressed into concavo convex form transversely and present their convexed faces to the base-plate. The base-plate A thus will not only fit very closely 75 at its scalloped or ornamental margins *a* to the face of the neck-strap, but the rein H in the holder cannot catch upon the margin of the plate A and be scratched thereby. Furthermore, the convexed inner faces of the holder-tongues B C, which hold the rein, will not 80 scratch or cut the rein.

It is obvious that rein-holders made as above described may be nickel, or silver, or gold plated, and will ornament the harness to which 85 they are attached, and as regards utility the holder prevents twisting of the rein slipped into them, and also prevents chafing of the neck-strap by the rein, and also prevents wearing the hair off the horse's neck, which occurs when the 90 rein is slipped under the neck-strap, and, what is most important of all, the holders, by their direct support of and clamping action or tension on the reins, prevent them from dropping in loops between the bit and the terrets when the 95 horse is standing in harness, and consequently prevents catching of the reins on the shafts or thills of a vehicle to which the horse is hitched, and also obviates the necessity of pulling in loose rein when the driver enters the vehicle 100

to drive farther, and the rein may be easily slipped from the holder by first pulling outward the extremity of the tongue B, to allow passage of the rein between the tongues B C, 5 and, finally, the rein-holder is very inexpensive to make or attach, and is very efficient and durable in use.

Having thus fully described my invention, I claim as new and desire to secure by Letters to Patent—

A rein-holder made of a single piece of elastic metal and comprising a base-plate, A, tongues B C, projecting from the ends of the

plate A and bent over the front thereof, and providing a rein-space, E, and the tongue C, 15 lapped upon the tongue B and having an out-bent end, e, and the opposing faces of the base-plate and tongues made convex transversely, and said plate A provided with attaching lips or tags D D, stamped from the body of the 20 plate, substantially as shown and described.

CHARLES EARNEST AUSTIN.
